FABRICATING MACHINE

Frank Y. Pearne, Los Angeles, Calif.

Application May 16, 1938, Serial No. 208,259

18 Claims. (Cl. 140—7)

This invention relates to means for connecting parts and relates more particularly to a machine for fabricating or tying together the parts of steel frames and like structures preparatory to the welding together of the parts. A general object of this invention is to provide a practical, rapid and effective machine for fabricating or connecting the several parts or elements of frames for reinforcing building structures, and for other purposes.

Another object of this invention is to provide a machine of the character mentioned that is operable to simultaneously tie two or more braces or like parts to a pair of spaced rods in connection with the fabrication of frames for reinforcing building structures, etc.

Another object of this invention is to provide a machine of the character mentioned that operates to securely tie or bind a transverse rod and one or more diagonal members to two spaced rods, or like parts, in one operation.

Another object of this invention is to provide a machine of the character mentioned in which the end portions of the transverse bar are curled or bent into eyes which grip the spaced side bars, as well as the diagonal member or members, to form strong, compact and dependable ties or connections ready for the welding operations.

Another object of the invention is to provide a machine of the character mentioned embodying two adjustably spaced units for performing two like operations simultaneously.

Another object of this invention is to provide a machine of the character mentioned that is fluid pressure operated and that is substantially automatic in operation.

Another object of this invention is to provide a machine of the character mentioned in which the forming parts or dies, as well as certain anvil dies, are automatically retracted at the completion of a cycle or operation to permit the rapid and easy advancement of the frame to position for a succeeding operation.

Another object of this invention is to provide a machine of the character mentioned that is fully controlled and operated by the manipulation of a single valve.

A further object of this invention is to provide a machine of the character mentioned that embodies simple, yet very effective, means for maintaining the spaced side rods, the transverse rods, and the diagonal member or members in the correct relation during the tying or connecting operation.

55 The various objects and features of my inven-

tion will be fully understood from the following detailed description of a typical preferred form and application of the invention, throughout which description reference is made to the accompanying drawings, in which:

Fig. 1 is a side elevation of the machine provided by the present invention, showing the parts in the normal positions. Fig. 2 is a fragmentary side elevation of the machine illustrating one side of one unit and the control valve. Fig. 3 is an enlarged fragmentary vertical detailed sectional view taken as indicated by line 3—3 on Fig. 1. Fig. 4 is a fragmentary vertical detailed sectional view taken as indicated by line 4—4 on Fig. 3. Fig. 5 is an enlarged fragmentary vertical detailed sectional view taken as indicated by line 5—5 on Fig. 1. Fig. 6 is an enlarged fragmentary vertical detailed sectional view taken as indicated by line 6—6 on Fig. 1. Fig. 7 is an enlarged horizontal detailed sectional view taken as indicated by line 7—7 on Fig. 1. Figs. 8, 9 and 10 are fragmentary illustrative side elevations showing the action of the forming parts or dies during the various phases of operation. Fig. 11 is a fragmentary elevation view of an assembly or frame of the character fabricated by the machine. Fig. 12 is an enlarged fragmentary vertical sectional view taken as indicated by line 12—12 on Fig. 11, and Fig. 13 is a diagrammatic view of the fluid pressure system and the cylinder and piston mechanisms for controlling and operating the machine parts.

The improved machine of the present invention has numerous uses, that is, it is useful in the manufacture of articles and structures of various natures. In the following detailed description I will describe the machine of the invention employed in connection with the fabrication or assembly of a frame useful in the construction and reinforcement of buildings, etc. It is to be understood that the invention is not to be construed as limited or restricted to this special use or application of the invention.

Fig. 11 of the drawings illustrates a portion of a frame of the nature constructed or fabricated by the machine of the invention. The portion of the frame illustrated includes two spaced side members or rods 10, a plurality of transverse rods 11 and one or more brace members or diagonal rods 12. The side rods 10 are in parallel relation and the transverse rods are spaced longitudinally of the side rods 10. In the particular case illustrated there are two like brace rods or diagonal rods 12 embodied in the frame structure. The brace rods 12 are of

zigzag shape, each having adjacent portions alternately pitched in opposite directions with respect to the longitudinal axis of the frame. The adjacent pitched portions of the rods 12 join at substantially right angled bends 13 and these bends 13 occur at the points of connection of the transverse rods 11 with the longitudinal rods 10. The parts of the frame may all be formed of round or cylindrical stock and, in the case illustrated, the side rods 10 are larger in diameter than the transverse rods 11 and the rods 11 are larger in diameter than the brace rods 12. The connections between the several parts of the frame as made by the machine will be herein-after described.

The machine of the present invention comprises, generally, a base 14, two units A adjustably supported on the base 14 and each including a standard 15, a pair of anvil dies C and D, cylinder and piston means 16 for operating or moving the anvil dies D, an initial forming and clamping die 17, cylinder and piston means 18 for operating the die 17, a forming die 19 and fluid pressure actuated means 20 for operating the die 19; and a fluid pressure system 21 for controlling and operating the cylinder and piston means 16 and 18 and the means 20 of the two units.

The base 14 may comprise an elongate plate 22 adapted to be suitably mounted or fixed on the floor or support carrying the machine. A pair of vertically spaced parallel track members 23 are arranged on the base plate 22. The lower track member 23 may be directly secured to the plate 22 as by welding, or the like, while the upper track member 23 may be secured to longitudinally spaced blocks 24. The opposite edges or side surfaces of the track members 23 lie in common vertical planes.

The standards 15 of the units A may be identical and are arranged in spaced opposing relation. The standards 15 are supported on the base 14 for adjustment or movement toward and away from one another. Each standard 15 may include two spaced upright or vertically disposed plates 25. The plates 25 of the standards 15 may be secured together by bolts 26. Spacers 27 are arranged on the bolts 26 to maintain the plates 25 in the desired spaced relation. The lower edges of the standard plates 25 engage or ride on the upper side of the base plate 22 and the standard plates 25 have their inner surfaces in sliding cooperation with the side surfaces of the track members 23. Pluralities of bolts 28 are arranged through openings in the adjacent standard plates 25 and the bolts 28 pass transversely through the space between the track members 23. It is believed that it will be apparent how the standards 15 of the units A may be shifted along the base 14.

The invention provides means for shifting or adjusting the units A to control or vary the space between them. This means includes nuts 30 arranged between the plates 25 of each standard 15. The nuts 30 have trunnions 31 received in openings in the adjacent standard plates 25. A screw 32 is arranged above the base 14 in parallel relation thereto and operates in the nuts 30. One end portion of the screw 32 has a right hand thread cooperating with one nut 30 and the other end portion of the screw has a left hand thread cooperating with the other nut 30. A post 33 on the base 14 may assist in supporting the screw 32. A hand wheel 34 may be provided on an end of the screw 32 to facilitate its adjustment or rotation. It is believed that it will be apparent how

the units A may be adjusted toward and away from one another by rotation of the screw 32. The bolts 28 may be tightened down to clamp the plate 25 against the track members 23 to hold the units A against movement in the set or adjusted positions.

The anvil dies C and D support the side rods 10 and the diagonal rods 12 and serve to support the transverse rods 11 through the medium of the side rods 10, and thus act as anvils during the forming 10 of the ties or connections. The standards 15 have notches 35 to receive the frame parts or work and the anvil dies C and D are located at the notches 35. The notches 35 are formed in the plates 25 of the standards 15 and the notches 15 35 of the two units A are aligned or in the same horizontal plane. The notches 35 are substantially C-shaped in side view having sides or mouths open at adjacent edges of the plates 25. The notches 35 of the units A face or open in 20 the same direction. The anvil dies C and D are mounted or arranged at the outer sides of the plates 25 and are in corresponding positions on the two units A, that is, the dies C are at one side of the machine and the dies D are at the 25 other side of the machine. Bolts or screws 36 may serve to fix the dies C to their respective plates 25. The dies C project upwardly to have their upper parts at or adjacent the central horizontal planes of the notches 35. Suitable 30 caps 37 may be provided on the upper ends of the dies C. The caps 37 are preferably fixed to the dies C and are removable. Notches 38 are provided in the tops of the caps 37 to partially receive the side rods 10 of the work or frame. 35 Flat substantially horizontal faces 39 extend outwardly from the notches 38 to support the bends 13 of the diagonal members or brace rods 12. The rear or inner walls of the notches 38 are preferably of substantial height to prevent the 40 rods from jumping or moving out of the notches. The dies C and their caps 37 preferably project inwardly to extend within the forming dies 19. The caps 37 of the dies C preferably present active surfaces of substantial area.

The anvil dies D are mounted or arranged for vertical movement between positions where their active upper faces are clear of the frame or work and positions where their active faces are in the same planes as those of the anvil dies C. The 50 dies D are shiftable on the outer sides of the adjacent standard plates 25 and are guided by suitable guides 40. The dies D and the guides 40 have overlapping parts so that the guides serve to hold the dies against lateral movement. Pins 41 55 on the standard plates 25 cooperate with vertical slots 42 in the dies D to limit the vertical movement of the dies. The upper ends of the dies D may have caps similar to the above described caps 37. In the particular case illustrated however, 60 the dies D are integral members and their upper ends have notches 38^a and faces 39^a corresponding in position and function to the above described notches 38 and faces 39, respectively. When the shiftable anvil dies D are in their up 65 or active positions their notches 38^a are in alignment with the notches 38 of the dies C and their faces 39^a are in the same horizontal planes as the faces 39.

The means 16 are provided to shift the anvil 70 dies D vertically between the active and retracted positions. There is a means 16 embodied in each unit A. Each means 16 includes a cylinder 43 at the outer side of a plate 25 and a piston 44 operable in the cylinder 43 and connected 75

with the adjacent die D. The cylinders 43 have their lower ends fixed to suitable brackets 45 on the plates 25. The upper caps or heads 46 of the cylinders 43 are held in place by nuts 48 threaded on rods 47 extending upwardly from the brackets 45. Rods 49 extend upwardly from the pistons 44, pass through openings in the heads 46 and have their upper ends secured to the lower portions of the dies D. The pistons 44 are provided with suitable cup leathers 49^a or similar sealing means effective against the pressures below them.

In accordance with the invention means are provided for returning the dies D to their retracted positions after each operation. These means may be in the nature of helical springs 50 surrounding the piston rods 49 and arranged under compression between the pistons 44 and the heads 46. The cylinder and piston means 16 just described are controlled and operated by the means 21 to be hereinafter described.

The dies 17 are provided to initially shape or form the transverse rods 11 of the work or frame and to grip or clamp against the work during the subsequent forming of the rods 11 by the forming dies 19. The dies 17 are blade-like parts shiftable or movable vertically between the upper portions of the spaced standard plates 25. The dies 17 are movable downwardly through slots in the dies 19 as will be subsequently described. The active or lower ends of the dies 17 are shaped to cooperate with a transverse rod 11 to initially shape the same and to clamp the work against the anvil dies C and D during the subsequent bending of the rod to form the tie or connection. The dies 17 have flat horizontal lower faces 52 to engage the upper side of the transverse bar 11 when moved downwardly. Notches 53 are provided in the inner lower corners of the dies 17 to shape the rod 11 to conform to the brace rods 12. As illustrated in Fig. 9 of the drawings the faces 52 are adapted to move against a transverse rod 11 to move or bend the major portion of it to occupy the same plane as the side rods 11 and to bend or shape the rod 11 to fit about the top of the brace rod or rods 12. It will be seen how the faces 52 cooperating with the transverse rod 11 hold the same against upward movement and against bending during the curling of the end portions of the rod about the longitudinal rods 10.

The means 18 are operable under the control of the means 21 to force or actuate the dies 17 downwardly against the work. There is one means 18 provided on the upper end of each standard 15. Each means 18 includes a cylinder 54 and a ram 55 operable in the cylinder. The cylinders 54 are vertically disposed to extend upwardly beyond the upper ends of the standards 15. Flared flanges 56 are provided on the lower ends of the cylinders 54 and are bolted or otherwise secured to the standard plates 25 to attach the cylinders to the standards. The upper ends of the cylinders 54 are closed and the rams 55 are adapted to move through or extend from the lower ends of the cylinders 54. Cup leathers 57 or other suitable sealing means are provided on the rams 55 to seal with the walls of the cylinders 54. Fluid under pressure is admitted to the upper ends of the cylinders 54 by the means 21 to force the rams 55 and the dies 17 downwardly. The upper ends of the dies 17 are fixed or secured to the rams 55 as by welds 58. The lower portions of the rams 55 are cut away to

have clearance with the spaced plates 25 of the standards 15.

In accordance with the invention spring means are provided for returning the rams 55 and the dies 17 at the termination of each operation of the machine. These spring means include rods 59 fixed to lugs 60 on the projecting lower portions of the rams 55. The rods 59 extend upwardly beyond the upper ends of the cylinders 54 and cross heads 61 are connected with the rods 10 by nuts 62. Springs 63 are arranged under compression between the cross heads 61 and the upper ends of the adjacent cylinders 54. The springs 63 acting on the cross heads 61 serve to automatically return the rams 17 and to normally hold the rams in their retracted positions. Stop screws 64 may be provided on the cross heads 61 to cooperate with the upper ends of the cylinders 54 and limit the downward travel of the dies 17 when there is no work in the machine. In accordance with the invention the springs 63 for returning the dies 17 are stronger than the springs 50 for returning the movable anvil dies D. This relationship between the springs 63 and 50 is important, as will be more fully described.

A bending or forming die 19 is embodied in each unit A to act on and bend an end portion of a transverse bar or rod 11. The dies 19 are in the nature of rotary dies or turnable dies and there is a die 19 arranged in each notch 35. The dies 19 are substantially C-shaped in side elevation and when in the normal or idle positions their open sides or mouths register with the mouths of the notches 35. The dies 19 are positioned to have their peripheries bear or turn on the walls of the notches 35. Peripheral tongues or ridges 65 are provided on the turnable dies 19 and project between the spaced plates 25 to hold the dies against lateral or longitudinal movement. It will be noted that the dies 19 turnably supported in the notches 35 have their lower portions positioned between the spaced anvil dies C and D. A slit or circumferentially extending slot 66 is provided in each die 19. The slots 66 are adapted to receive or pass the end portions of the rods 11 to be acted on and are adapted to receive the dies 17 with suitable clearance. As best illustrated in Fig. 4 of the drawings the slots 66 are of substantial length or circumferential extent and communicate with or intersect the open sides or mouths of the C-shaped dies 19.

An axially extending part 67 crosses or intersects each slot 66 and serves to connect the two ring-like portions of the respective dies 19. The parts 67 are the active elements of the dies 19 and project inwardly into the interiors of the dies to cooperate with the work. The inner surfaces 68 of the die parts 67 are curved concentric with the axes of rotation of the dies 19. The active sides of the die parts 67, that is, the sides of the parts that move against the rods 11, are tangential relative to circles concentric with the axes of the dies 19. It is preferred to provide the active inner corners of the parts 67 with hard inserts 69. The dies 19 are normally in rotative positions where their active parts 67 are out of the path of travel of the dies 17. When the dies 19 are turned the inserts 69 come into cooperation with a rod 11 and as the rotation is continued this engagement causes the end portions of the rod to be bent or wrapped about the longitudinal rods 10. The curved inner surfaces 68 of the parts 67 may assist in

this bending or curling of the rod 11. Turning of the dies 19 continues until the ends of the rod 11 are brought against the body of the rod 11 or against the angle bends 13 in the brace rods 12. It is to be understood that the dies 19 face one another and turn in opposite directions to form the eyes in the end portions of the rod 11. A fluid pressure actuated means 20 is embodied in each unit A to operate its die 19. Each means 20 includes a cylinder 70 suitably fixed to a side plate 25 and a piston 71 operable in the cylinder. The opposite ends of the cylinders 70 are closed and the pistons 71 are moved in both directions by fluid under pressure, as will be subsequently described. Rods 72 extend upwardly from the pistons 71 and pass through packing glands 73 on the upper ends of the cylinders 70. The means further include racks 74 suitably connected with or secured to the upper ends of the rods 72. Rollers 101 are rotatably supported on pins 102 to guide the racks 74. Shafts 75 are rotatable in aligned horizontal openings 76 in the standard plates 25 and the stationary anvil die C. The shafts 75 project outwardly beyond the dies C and their projecting portions carry pinions 77 which mesh with the racks 74. The pinions 77 are fixed to the shafts 75. Gear teeth 78 are provided on the ridges or flanges 65 of the dies 19 and pairs of pinions 79 are fixed to the shafts 75 to mesh with the teeth 78. From an inspection of Fig. 1 of the drawings it will be seen that the racks 74 cooperate with the opposite sides or the outer sides of the pinions 77 so that actuation or upward movement of the racks 74 results in turning of the dies 19 in opposite directions. Upward movement of the racks 74 with the pistons 71 turns the dies 19 from the idle positions shown in Fig. 8 of the drawings to the actuated positions shown in Fig. 10 of the drawings and the downward movement of the pistons 71 and racks 74 returns the dies.

The fluid pressure system 21 includes a tank 81 for containing a supply of suitable fluid such as oil and a pump 82 drawing the fluid from the tank 81. Reference may be had to Fig. 13 of the drawings for a disclosure of the relationship between the several elements of the means 21. An outlet pipe or high pressure pipe 83 extends from the pump 82 to the machine. A return or bypass line 84 may connect the high pressure pipe 83 with the tank 81 and may be under the control of a pressure relief valve 99 which opens to permit a by-passing of the fluid when the pressure builds up in the system to beyond a given pressure. The means 21 includes a master valve or control valve V for controlling the delivery or circulation of the fluid under pressure from the pipe 83 to the various cylinder or piston units of the machine. The valve V may be suitably mounted on one of the standards 15 and is in the nature of a four way valve. The valve V will be hereinafter described.

A pipe 85 extends from the valve V to the lower ends of the cylinders 43 of the means 16. The pipe 85 has a branch 85^a delivering the fluid under pressure to the upper ends of the cylinders 54 of the means 18. The pipe 85 and its branch 85^a have flexible sections 86 extending between the cylinders of the means 16 and 18 on the two units A so that they do not interfere with the adjustment of the units on the base 14. A line or pipe 87 extends from the line 85 and delivers fluid under pressure to the lower ends of the cylinders 70 of the means 20. The pipe 87 has a flexible portion 87^a interposed between the

two means 20 to permit free relative movement of the units A. A spring-held valve or a pressure relief valve 93 is interposed in the pipe 87 to normally close the same and to pass the fluid under pressure to the cylinders 70 when the pressure in the cylinders 54 builds up to a given point. A by-pass 99 extends around the valve 93 and has a check valve 90 permitting a return flow through the pipe 87. A pipe 91 extends from the valve V to the upper ends of the cylinders 70 and has a flexible portion 91^a between the cylinders. A fluid return pipe 92 extends from the valve V to the supply tank 81 and is under the control of a check valve 93 that prevents back flow from the tank. 15

The valve V is in the nature of a manually operable control valve and is provided to govern the flow through the pipes 85, 91 and 92. The present invention is not primarily concerned with the details of the valve V and a more or less conventional four-way piston type valve has been diagrammatically illustrated in Fig. 13. The valve V shown in the drawings includes a body 94, a piston type valve element 95 in the body 94 and a suitable lever 96 for operating or shifting the element 95. The pipe 85 and the pipe 91 communicate with the interior of the valve body 94 at longitudinally spaced points. The fluid pressure supply pipe 83 is branched to communicate with the opposite end portions of the valve body 94. The return pipe 92 communicates with the valve body 94 at a point between the pipes 85 and 91. The valve element 95 is grooved or shaped so that the pipes 85 and 91 are both in communication with the return pipe 92 when the element is in its neutral or intermediate position. With the valve element 95 in the neutral position the pipes 85, 91 and 92 are in communication with the pressure supply pipe 83. When the valve element 95 is moved downwardly the pipe 85 is put in communication with the pipe 83 so that fluid under pressure is supplied to the pipe 85 to effect the actuation of the means 16, 18 and 20. When the valve element 95 is moved upwardly or in the opposite direction beyond the neutral position the pipe 91 is put into communication with the pressure supply pipe 83 and the pipe 85 is placed in communication with the fluid return pipe 92 so that the means 16, 18 and 20 are returned to their normal conditions 30 as will be more fully described. 35

In the use or operation of the machine the longitudinal rods 13 of the frame are arranged in the notches 38 of the stationary anvil dies C. The movable anvil dies D are in their down or retracted positions at this time. When the frame has been positioned with the rods 10 in the notches 38 and with the bends 13 of the diagonal rods 12 at or resting on the surfaces 39, a transverse rod 11 is arranged in place to overlie or rest on the two side rods 10. The rod 11 may be readily passed between the standard plates 25 and through the slots 66 and the slots 66 serve to center or position the rod 11 directly above the bends 13 in the rod or rods 12. The parts are then positioned for the tying or connecting operation. 55

The operator may move the lever 96 downwardly to place the pipe 85 in communication with the pressure supply pipe 83. The fluid under pressure thus supplied to the pipe 85 acts on the pistons 44 and the rams 55. As the springs 52 are weaker than the springs 63 this fluid pressure moves the pistons 44 upwardly before sufficient pressure has built up to move the rams 75 70

55 downwardly. Thus the movable anvil dies D are brought to their operative positions in engagement with the work before the dies 17 move downwardly. The dies 17 move downwardly under the action of the fluid pressure on the rams 55 and their surfaces 52 engage the upper side of the transverse rod 11 and the walls of their notches 53 cooperate with the rod 11. The dies 17 bend or force the major portion of the rod 11 downwardly and bend or shape the rod so that it partially conforms to the bends 13 of the rods 12. Fig. 9 of the drawings illustrates the manner in which the dies 17 initially shape the rod 11. The dies 17 also grip the work or clamp the 15 work down against the anvil dies C and D.

Upon the actuation of the dies D and the dies 17, as described above, the pressure on the fluid builds up in the pipes 85 and 87 and overcomes or opens the valve 88 and thus the fluid pressure 20 is delivered to the lower ends of the cylinders 10. The fluid pressure supplied to the lower ends of the cylinders 10 moves the pistons 71 upwardly. Upon upward movement of the pistons 71 the racks 16 cooperate with the pinions 77 to rotate 25 the shafts 15. The pinions 79 on the shafts 15 cooperating with the teeth 18 turn the dies 19. The dies 19 in turning bend the end portions of the rod 11 and wrap them about the rods 10 and the bends 13 and form the eyes 100. The die parts 67 act on the end portions of the rod 11 to wrap or bend them about the rods 10. The dies 19 form the eyes 100 so that they tightly grip the rods 10 and have their end portions 30 engaging up against the bends 13 of the rods 12 so that the eyes serve to secure the rods 10, 11 and 12 together.

Upon the completion of the connections or ties the operator moves the lever 96 upwardly to cut off the pipe 85 from the supply pipe 83 and to 40 deliver fluid under pressure from the pipe 83 to the pipe 91. Upward movement of the valve element 95 puts the pipe 85 in communication with the return pipe 92 and the springs 50 acting on the pistons 44 return the dies D and the springs 45 63 return the dies 17. The fluid under pressure delivered to the pipe 91 as just described, acts on the pistons 71 to turn the dies 19 back to their initial positions. The frame may then be removed from the machine or may be advanced 50 through the machine for another operation. It is to be particularly noted that the retraction of the anvil dies D permits the easy longitudinal movement of the frame through the machine for removal or for a succeeding operation. When the 55 dies D are retracted the eyes 100 may be moved through and out of the notches 35 without interfering with the dies D. This greatly simplifies the handling of the frame and makes it unnecessary to lift or shift the frame vertically to disengage the eyes 100 from the die parts.

The machine of the present invention is capable of rapidly forming the ties or connections between the several parts of the frame and at each 60 operation simultaneously forms two ties or connections. The machine is such that the work or frame may be easily fed through it during the fabrication of the frame. The action or operation of the die mechanisms is substantially automatic, that is, the die parts operate in the proper sequence without manual manipulation.

Having described only a typical preferred form and application of my invention, I do not wish to be limited or restricted to the specific details herein set forth, but wish to reserve to myself any 75 variations or modifications that may appear to

those skilled in the art or fall within the scope of the following claims.

Having described my invention, I claim:

1. A machine for tying a cross rod to spaced rod members comprising means for supporting said members in a given relation, means for offsetting the major intermediate portion of the cross rod to lie in substantially the same plane as the rod members and for holding the cross rod in a given position against the said members, and means for bending the end portions of the cross rod around the said spaced members. 5

2. A machine for securing a cross rod and one or more diagonal rods to spaced rod members comprising means for offsetting the major intermediate portion of the cross rod to lie in substantially the same plane as the rod members and the diagonal rod and for clamping the cross rod against the diagonal rod and the spaced rod members, and means for bending the end portions of the cross rod about the spaced members and the diagonal rods while so clamped. 15

3. A machine for tying a cross rod to spaced rod members and diagonal rods located between the rod members, the machine comprising means 25 for supporting said members and the diagonal rods in a given relation, means for clamping the cross rod in a given position against the members and the diagonal rods, and means for bending the end portions of the cross rod around 30 the spaced members and the diagonal rods.

4. A machine for tying a cross rod to spaced rod members comprising means for supporting said members in a given relation, means for holding the cross rod in a given position against 35 the members, and means for bending the end portions of the cross rod around the spaced members, the last named means comprising a turnable die for acting on each end portion of the cross rod, the said dies having slots receiving 40 said end portions, and means for turning the dies.

5. In a machine for securing a cross rod to a second rod, two anvil dies, one anvil die being stationary, the other being shiftable, the dies being shaped to support the second rod in a given position, a gripping die operable against the cross rod to hold the rods in a given relation, means for shifting the movable anvil die to the supporting position, means for operating the gripping die, means for bending the cross bar around the second bar while the gripping die and the anvil die are actuated to form an eye on the cross bar to connect it with the second bar, and means for retracting the movable anvil die and the gripping die following the bending operation to facilitate 55 advancement of the rods. 50

6. A machine for connecting transverse rods with spaced longitudinal rods and diagonal rods located between the longitudinal rods, the machine comprising two spaced units each including anvil means for supporting a longitudinal rod and a diagonal rod in a given relation, a gripping die for holding a transverse rod against the said longitudinal rod and diagonal rod, and a bending die for bending an end portion of the 60 said transverse rod about the said longitudinal rod and said diagonal rod, and means for operating the gripping dies and the bending dies. 65

7. A machine for connecting transverse rods with spaced longitudinal rods comprising two 70 spaced units each including anvil means for supporting a longitudinal rod in a given position, a gripping die for holding a transverse rod against the said longitudinal rod, and a bending die for bending an end portion of the said trans- 75

- verse rod about the said longitudinal rod, the said anvil means comprising a stationary anvil die and a shiftable anvil die, means for operating the gripping dies and the bending dies, means for shifting the shiftable anvil dies to the active positions prior to actuation of the gripping dies, and means for retracting the gripping dies and the shiftable anvil dies following the bending operation.
10. A machine for connecting transverse rods with spaced longitudinal rods comprising two spaced units each including anvil means for supporting a longitudinal rod in a given position, a gripping die for holding a transverse rod against the said longitudinal rod, a bending die for bending an end portion of said transverse rod about the longitudinal rod, cylinder and piston means for operating the gripping die, and cylinder and piston means for operating the bending die, and a single fluid pressure system for operating the several cylinder and piston means.
9. A machine for connecting transverse rods with spaced longitudinal rods and one or more diagonal rods located between the longitudinal rods, the machine comprising two spaced units each including anvil means for supporting a longitudinal rod and a diagonal rod in adjacent relation, a gripping die for holding a transverse rod against the said longitudinal rod and the said diagonal rod, and a bending die for bending an end portion of the said transverse rod about the said longitudinal rod and the said diagonal rod to connect the three rods, means for adjusting said units toward and away from one another, and means operating the gripping dies and the bending dies.
10. A machine for securing transverse rods and diagonal rods to spaced side rods comprising two units, each unit including a pair of anvil dies for supporting the side rods and the diagonal rods in a given relation, one anvil die being shiftable, a clamping die for holding a transverse rod against the side rods, a slotted turnable bending die for bending an end portion of the said transverse rod about the side rod and a diagonal rod, fluid pressure actuated mechanisms for shifting the shiftable anvil die and for actuating the clamping die and the bending die, and means for restoring the shiftable anvil die and the clamping die, and a fluid pressure system for supplying actuating fluid pressure to said mechanisms of the said units.
11. A machine for securing transverse rods and diagonal rods to spaced side rods comprising two units, each unit including, a pair of anvil dies for supporting the side rods and the diagonal rods in a given relation, one anvil die being shiftable, a clamping die for holding a transverse rod against the side rods, a slotted turnable bending die for bending an end portion of the said transverse rod about the side rod and a diagonal rod, fluid pressure actuated mechanisms for shifting the shiftable anvil die and for actuating the clamping die and the bending die, and means for restoring the shiftable anvil die and the clamping die, and a fluid pressure system for supplying actuating fluid pressure to said mechanisms of the said units, the restoring means comprising springs, the springs restoring the shiftable anvil dies being of less strength than the springs restoring the clamping dies whereby the fluid pressure effects movement of the shiftable anvil dies against the work prior to actuation of the clamping dies.
12. In a machine for connecting two members arranged in crossed relation, two spaced anvil dies for supporting one of said members, one of said anvil dies being shiftable into and out of supporting position, a clamping die in a plane spaced between the anvil dies and operable to clamp the other member against the first named member, a turnable bending die between the anvil dies having a slot receiving said other member and receiving the clamping die, means for shifting the shiftable anvil die, means for operating the clamping die, and means for operating the bending die.
13. In a machine for connecting two members arranged in crossed relation, two spaced anvil dies for supporting one of said members, one of said anvil dies being shiftable into and out of supporting position, a clamping die in a plane spaced between the anvil dies and operable to clamp the other member against the first named member, a turnable bending die between the anvil dies having a slot receiving said other member and receiving the clamping die, separate cylinder and piston means for shifting said shiftable die and for operating the clamping die and the bending die, a source of fluid pressure, and a single valve controlling the delivery of fluid under pressure to said separate means.
14. A machine for securing a cross rod and one or more diagonal rods to two spaced generally parallel longitudinal rods, the machine including means supporting the longitudinal rods and the diagonal rods, means for offsetting the major portion of the cross rod to lie in substantially the same plane as the longitudinal and diagonal rods and for clamping the cross rod against the longitudinal rods and the diagonal rods, and means for bending the end portions of the cross rod about the longitudinal rods and the diagonal rods to connect the several rods.
15. A machine for securing a cross rod and one or more diagonal rods to two spaced generally parallel longitudinal rods, the machine including means supporting the longitudinal rods and the diagonal rods, fluid pressure operated means for offsetting the major portion of the cross rod to lie in substantially the same plane as the longitudinal and diagonal rods, fluid pressure operated means for bending the end portions of the cross rod about the longitudinal rods and the diagonal rods to connect the several rods, and a fluid pressure system for operating the said fluid pressure operated means in sequence.
16. A machine for securing a cross rod and one or more diagonal rods to two spaced generally parallel longitudinal rods, the machine including means supporting the longitudinal rods and the diagonal rods, fluid pressure operated means for offsetting the major portion of the cross rod to lie in substantially the same plane as the longitudinal and diagonal rods, fluid pressure operated means for bending the end portions of the cross rod about the longitudinal rods and the diagonal rods to connect the several rods, and a fluid pressure system for actuating the said fluid pressure operated means in sequence including a manual valve operable to cause actuation of the said fluid pressure operated means in sequence.
17. A machine for securing a cross rod and one or more diagonal rods to two spaced generally parallel longitudinal rods, the machine including two units, each unit comprising means for supporting a longitudinal rod and a diagonal rod in a substantially common plane, means for bending the cross rod to offset its inner part to lie in

said plane, and for clamping the cross rod against said longitudinal rod and said diagonal rod, means for bending an end portion of the cross rod about the said longitudinal rod and the said diagonal rod, and separate fluid pressure means for operating the two bending means.

5 18. A machine for tying a cross rod to spaced rod members comprising means for supporting

said members in a given relation, separate fluid pressure actuated means for clamping the cross rod against the rod members to hold the cross rod in a given position, and separate fluid pressure actuated means for bending the end portions of the cross rod around the spaced members.
